UNITED STATES PATENT OFFICE

102,639

DESIGN FOR A CONFECTIONERY PRODUCT

Louis B. Olin, Chicago, Ill.

Application May 29, 1936, Serial No. 62,906

Term of patent 3½ years

To all whom it may concern:

Be it known that I, Louis B. Olin, a citizen of the United States, residing at Chicago, in the county of Cook and State of Illinois, have invented a new, original, and ornamental Design for a Confectionery Product, of which the following is a specification, reference being had to the accompanying drawing, forming a part thereof.

tionery product with its handles, and shows my new design;

Figure 2 is a cross sectional view on the line 2—2 of Figure 1 and shows the shape of the confectionery product of my new design.

I claim:

The ornamental design for a confectionery product as shown.

LOUIS B. OLIN.
